UNITED STATES PATENT OFFICE.

JESSE G. ROSEBOOM, OF NORFOLK, VIRGINIA.

SASH-FRAME AND SASH.

No. 863,098.

Specification of Letters Patent.

Patented Aug. 13, 1907.

Application filed June 6, 1907. Serial No. 377,566.

To all whom it may concern:

Be it known that I, JESSE G. ROSEBOOM, a citizen of the United States, residing at Norfolk, in the county of Norfolk and State of Virginia, have invented new 5 and useful Improvements in Sash-Frames and Sashes, of which the following is a specification.

My invention relates to sash frames and sashes, and more particularly to those designed to be made of metal; and it has for one of its objects to provide a 10 sash frame, a sash, a wind-guard movable with the sash, and a counterbalance weight, all so constructed and relatively arranged that the wind-guard and weight may be readily placed in position, and when necessity demands ready access may be had to the wind-guard 15 and weight for repairs or other purposes.

Another object of the invention is the provision of a sash-balancing weight in the form of a case containing heavy material, either in one piece or in bulk, and provided with a discharge opening controlled by 20 a fusible closure, this in order that when the lower sash is in its upper position and a fire takes place, the heat will melt the fusible closure and permit the heavy material to gravitate out of the case and thereby enable the sash to drop to its closed position.

25 Another object is the provision of an upper sash containing heavy material in comminuted form and provided with a discharge opening for such material and a fusible closure for such opening, so that when a fire occurs while the upper sash is in its lower position, the fusible closure will be melted and the heavy material permitted to pass from the sash with the result that the ordinary or any other suitable weights complementary to the sash will raise the same to its closed position.

35 Another object is the provision of means in the lower portion of a frame stile designed to coöperate with a sash-balancing weight with a view of preventing the weight as it passes down toward the lower end of the stile from swinging out of the stile.

40 With the foregoing in mind, the invention will be fully understood from the following description and claims when the same are read in connection with the accompanying drawings, forming part of this specification, in which:

45 Figure 1 is a vertical section illustrating a sash-frame and sashes constructed in accordance with my invention. Fig. 2 is a horizontal section taken through the frame and sashes. Fig. 3 is a broken sectional perspective view, on an enlarged scale, showing the 50 relative arrangement of the frame, the lower sash, a wind-guard, a counterbalance-weight and the cable intermediate the wind-guard and the counterbalance weight. Fig. 4 is a sectional view of one of the counterbalance-weights complementary to the lower sash. 55 Fig. 5 is a detail section, on an enlarged scale, showing the discharge opening of the upper sash, the heavy

comminuted material in said sash, and the fusible closure of the opening. Fig. 6 is a detail section showing a guide for one counterbalance-weight of the lower sash. Fig. 7 is a detail section showing the connection of one cable of the lower sash to the mud guard thereof. 60

Similar letters designate corresponding parts in all of the views of the drawings, referring to which:

A A are the side stiles of a metallic sash frame. 65 These stiles are joined to a head and a sill in the ordinary or any other suitable manner and are provided with two guideways a and b; the former being for the lower sash and the latter for the upper sash.

B is the lower sash, and C is the upper sash. The 70 lower sash B is provided in the outer sides of its vertical bars with grooves c and is also provided at the upper ends of said grooves with apertured plates d for a purpose presently set forth.

D D are wind-guards, preferably of I-form in cross- 75 section, arranged in the opposed grooves a and c of the stiles A and sash B, respectively, and under the plates d of said sash.

E E are the counterbalance-weights complementary to the sash B; said weights being located in the outer 80 portions of the wind-guards; and F F are cables, preferably cords as shown, extending between and connected to the wind-guards D and weights E and also extending over sheaves or pulleys G, mounted in the upper portions of the side stiles A, or else in the head of the frame, 85 as shown. The wind-guards D bear at their upper ends against the undersides of the plates d on sash B, and hence it will be apparent that when the sash is raised, the gravitation of the weights E by pulling the wind-guards D upward will render easy the raising of the 90 sash. It will also be apparent, in this connection, that when sash B is moved downward, the wind-guards D will also be moved downward and the weights E will be raised, with the result that the weights will balance the sash. 95

By virtue of the construction and relative arrangement of the parts described, it will be seen that the weights, wind-guards and sash may be expeditiously and easily arranged in the frame; also, that when necessary for repairs or any other purpose ready access may 100 be gained to the weights. The wind-guards D extend the full height of the sash B, and, as their name implies, serve to preclude the passage of drafts of air between the sash and the stiles A.

As best shown in Fig. 4, the weights E respectively 105 comprise a case e having a discharge opening f in its lower end or at any other suitable point, heavy material g, preferably though not necessarily in a comminuted state, arranged in the case e, and a fusible closure h which under normal conditions serves to retain 110 the heavy material in the case e—i. e., against dropping through the opening f. When, however, a fire occurs in

the vicinity of my improved sash frame and sashes, it will be seen that the fusible closures *h* of the weight-cases *e* will be melted, whereupon the heavy material *g* will pass from said cases *e*. In consequence of this the 5 sash *B* will gravitate to its closed position, and in that way close the window and lessen the liability of the fire spreading.

With a view of preventing swinging of the weights *E* as the same approach the lower ends of their traverse, I 10 provide in the grooves *a* of the stiles *A*, fixed vertical rails *H* of T-form in cross section, the heads of which are arranged to enter correspondingly-shaped grooves *I* in the outer sides of the weight cases *e*. Thus when the weights *E* approach the lower ends of the stiles *A* there 15 is no liability of the weights swinging out of the stiles.

J J are the wind-guards complementary to the upper sash *C*.

K K are the weights for the upper sash, and *L L* are cables passed over sheaves *M* mounted in the upper 20 portion of the sash frame and connecting the weights *K* and the wind-guards *J*. The stiles *A*, sash *C*, wind-guards *J*, weights *K*, and cables *L* are relatively arranged in the same manner as the stiles *A*, sash *B*, wind-guards *D*, weights *E* and cables *F*, and need not there- 25 fore be described, except to say that the wind-guards *J* bear against apertured plates similar to the plates *d* at the upper ends of the grooves of sash *C*, and the weights *K* may be and preferably are of the ordinary well known type.

30 The upper sash *C* is peculiar in that its lower, hollow bar *m* contains heavy material *n* in a comminuted state, and is provided with an opening *p* normally closed by fusible material *q*. From this it follows that in the event of fire in the vicinity of my improvements while 35 the sash *C* is in its lower or open position, the closure *q* will be melted, when the heavy material *n* will pass through the opening *p* until the sash *C* is lighter than its weights *K* when the weights will obviously raise the sash *C* to its closed position and in that way tend to pre- 40 vent the spread of the fire.

In addition to the practical advantages hereinbefore ascribed to my improved metallic sash frame and sashes, it will be noted that the structure as a whole is compact and neat in appearance, and, at the same time, is well adapted to withstand the usage to which sash 45 frames and sashes are ordinarily adapted.

While designed more particularly for use in metallic sashes and sash frames, I desire it understood that such of my improvements as are applicable may be used in sash frames and sashes of wood or any other material 50 without involving departure from the scope of my invention as claimed.

Having described my invention, what I claim and desire to secure by Letters-Patent, is:

1. The combination of the side stile of a sash frame; 55 said stile having a vertical groove or guide-way at its inner side, a sheave mounted in the frame, a vertically slideable sash having a groove in the outer side of its side bar and also having an apertured arm at its upper end, a vertically-movable guard, of I-form in cross-section, arranged 60 in the opposed grooves of the stile and sash and under the overhanging arm of the latter, a weight movable in the outer portion of the guard, and a cable passed over the sheave and through the overhanging arm of the sash and connecting the guard and the weight. 65

2. The combination of a sash frame, a vertically slideable sash, a cable connected to the sash and passed over a sheave, and a weight connected to the cable and comprising a case having a discharge opening, a fusible closure therefor, and heavy material contained in the case and adapted when said fusible closure is melted to drop from the case. 70

3. The combination of the side stile of a sash frame, a T-rail fixed in the lower portion thereof, a vertically slideable sash, a sheave, a cable passed over the sheave and 75 connected to the sash, and a weight connected to the cable and movable in the stile and having a correspondingly shaped groove arranged to receive the said T-rail.

In testimony whereof I have hereunto set my hand in presence of two subscribing witnesses.

JESSE G. ROSEBOOM.
